FILTERING ELEMENT

Claude François Albert Chamouton, Paris,
France, assignor to Societe de Constructions
Mecaniques de Stains, a corporation of France

Application March 17, 1938, Serial No. 196,550
In France March 18, 1937

5 Claims. (Cl. 210—195)

This invention relates to filters, and more particularly to filter elements to be used in filter presses.

Prior to this invention, bag filters utilized pocket-shapes of cloth specially cut out and sewn for lining or enveloping their elements.

These bags had a number of drawbacks and disadvantages:

1. Since they had to be previously manufactured, they were high in price.

2. Since the bags had to be carefully sewn after the insertion of the elements, the application thereof to the elements required considerable time.

3. They required joints for the orifices provided therein to permit the passage of the evacuation conduits of the elements.

4. The filtration was often insufficient. Leaks were present or developed in the numerous seams, either on account of defective manufacture or the distention of the threads during use, especially when the cloths were "rejuvenized" or cleaned by means of the reverse circulation of liquid or compressed air.

Moreover, it had been proposed to replace the bags by two simple cloths applied respectively on each face of the element. The edges of these simple cloths were positioned in a groove provided in the frame of the element and secured therein by clamping, as by forcibly inserting a bead made of a thread of malleable metal, such as lead, or of textile braid.

That device did not find practical use on account of the following drawbacks:

1. The positioning of the cloths in place on the elements required too much time.

2. The means for securing the cloths deteriorated the cloths, both while being applied to the elements and during use.

3. Frequently the clamping was insufficient to resist the interior pressure during "rejuvenizing."

The present invention, which overcomes the above-mentioned defects and disadvantages, consists in a special device for securing (clamping) two cloths applied to the faces of a filtering element, and exhibits the following characteristics:

1. The mounting and application of the cloths to the filtering element are extremely easy and can be performed in a very short interval of time (less than a minute).

2. Perfect tightness is insured on the whole circumference, and there are no joints around the evacuation conduits of the elements.

3. The cloths do not suffer any tension, and forcible folding that may lead to its being torn or worn out rapidly is avoided.

The accompanying drawing, forming a part 5 of this specification, shows by way of example, which is not limitative, an illustrative embodiment of one form of the invention, and wherein:

Figure 1 is an elevation view of an element of 10 a bag filter, for example of the Sweetland type;

Figure 2 is an enlarged cross-section taken on lines *a*—*a* of Figure 1; and

Figure 3 is an enlarged partial elevation showing the manner of fixing and stretching the binding.

15 According to the principles of this invention, there is provided an element comprising a metal cloth appropriately secured in or to a rim having one or more grooves in its peripheral surface. On each face of the element, there is provided a disc 20 of a filtering medium, such as cloth, etc. The disc of filtering medium is of such dimensions as to permit the marginal portion thereof to extend into and be positioned in the groove in the rim. To secure the disc of filtering medium, a binding of any suitable material is wound on the portion of the disc in the groove. The ends of the binding material are appropriately secured to the rim or appurtenant elements so that the 25 securing of the filtering disc in place may be effected in a very short interval of time. In one form of the invention, the binding is provided at one end thereof with means, such as a button, whereby it can be positioned in an opening in a support disposed on the rim and secured therein

30 upon application of tension to the opposite end thereof. The opposite end of the binding is threaded and, after passing through a slot or hole in a boss or lug carried by the rim, cooperates with a nut which is screwed thereon. Thus, upon 35 screwing of the nut onto the threaded end of the binding, the latter will securely clamp the filtering disc in position on the element.

40 As is apparent from the foregoing, the filtering discs are secured in position on each face of the rim by means of binding circularly wound on the rim. Any number of windings may be employed. Satisfactory results have been secured when the binding extends at least 360° in the grooved 45 periphery.

50 The rim is provided with attachments whereby an evacuation conduit may be secured to the element. If desired, the evacuation conduit and its appurtenant parts may be formed integrally 55 with the rim. Likewise, the support provided

with the opening which is to cooperate with one end of the binding may be secured to the attachments for the evacuation conduit.

The metal fabric may be secured in the rim in any suitable manner.

In order to more clearly explain the invention, reference is now made to the accompanying drawing wherein like reference numerals designate like parts, and wherein the element comprises a rim 1 having two spaced grooves 1a and 1b in the peripheral surface thereof and enclosing a disc of metal fabric 2. The rim 1 carries an evacuation conduit 3 for the filtered liquid which, as shown in Figure 3, communicates with the interior of the complete filtering element. A 10 pair of attachments 4, hereinafter more fully explained, is rigidly secured to and mounted on the outside of the rim 1. In the form shown, the conduit 3 is adjacent to and intermediate the attachments 4. Each attachment 4 consists of a 15 plate appropriately secured to the conduit 3 or rim 1, or both, as desired, and provided with holes 6 communicating with slots 6', constituting what is generally termed a "keyhole" slot. Two obliquely placed ears or lugs 5 are also securely fixed and carried adjacent the peripheral surface of the rim 1 for reasons which will become apparent. The rim 1 may be made of various shapes and forms, and the metal fabric 2 secured thereto in any desired manner. In the 20 form shown, the under surface of the rim is provided with a flange 15 adjacent the edge thereof.

A disc 8 of cloth or any other material suitable for filtering purposes is applied to each face of the rim 1. Each disc 8 is of such dimensions that the marginal portion thereof extends in the groove 1a or 1b, as the case may be, where it is securely clamped by means of metallic binding 7 consisting, in the form shown, of steel wires. The steel wires 7 are detachable and extend in the respective grooves for about one turn and a quarter.

The ends are so secured as to exert an adjustable traction on the wire. In one embodiment, one end 10 of each binding is bent at a right angle and provided with a knob or button 11 which cooperates with the respective hole 6 and slot 6'. The other end 12 of the binding 7 is threaded and engages a slot 13 of the lug 5. A 35 nut 14, screwed on the threaded end 12 and bearing on the lug 5, permits traction to be exerted on the binding 7. The traction exerted by the nuts 14 on the bindings 7 forces the edge of the filtering disc strongly into the groove of the rim and the bindings securely clamp the same.

As shown in the drawing, clearances are provided for the free passage of the discs 8 between the edge of the rim and the attachment pieces of the bindings.

Though in the specific embodiment, the rim 1 is provided with a pair of grooves 1a and 1b, one for each disc 8, it is clear that only one groove may be used. In this embodiment, only one binding element 7 and one set of appurtenant 65 elements would be required.

If desired, both ends of the bindings may be threaded and secured by means of nuts 14 cooperating with the lugs 5.

The shape of the lugs 5 may vary considerably, 70 it being only necessary that the passage of the bindings, slots, holes or bosses shall be disposed in such a manner that the bindings are not released during and after clamping.

It is quite evident that the example of an em-

bodiment that has been given is in no manner limitative and that the present patent also covers every variation derived from the same conception.

5 I claim:

1. A filtering element comprising a rim having a peripheral groove therein, a disc of a filtering medium on at least one face of the rim and having the marginal portion thereof disposed in said groove, a binding disposed in said groove and on said marginal portion, said binding having a button on one end thereof and a threaded portion adjacent the other end thereof, said binding being wound in said groove and extending over at least the entire circumference thereof, means disposed on said rim to cooperate with the button end of the binding, means disposed on the rim permitting a nut to cooperate with said threaded portion to exert an adjustable tension on said binding, and a nut screwed on said threaded portion.

2. A filtering element comprising a rim having a peripheral groove therein, a disc of a filtering medium on at least one face of the rim and having the marginal portion thereof disposed in said groove, a binding disposed in said groove and on said marginal portion, said binding having a button on one end thereof and a threaded portion adjacent the other end thereof, said binding being wound in said groove so that it extends approximately one and one quarter turns in said groove, means disposed on said rim to cooperate with the button end of the binding, means disposed on the rim permitting a nut to cooperate with said threaded portion to exert an adjustable tension on said binding, and a nut screwed on said threaded portion.

3. A filtering element comprising a rim having a peripheral groove therein, means disposed on 40 said rim having a slotted hole, means disposed on said rim having a keyhole slot, a disc of a filtering medium on at least one face of the rim and having the marginal portion thereof disposed in said groove, a binding wound for at least one full turn in said groove and disposed on said marginal edge, said binding having one end thereof provided with a button and the other end thereof being threaded, said button adapted to secure the binding adjacent thereto in said slotted hole, the threaded end extending through said keyhole slot and cooperating with a nut whereby an adjustable tension on said binding is secured.

4. A filtering element comprising a rim having 55 a groove in the peripheral surface thereof, a disc of a filtering medium on at least one face of the rim and having the marginal portion thereof disposed in said groove, a binding engaging said marginal portion to secure said marginal portion in said groove, one end of said binding being secured adjacent the periphery of said rim, said binding having a threaded portion adjacent the other end thereof, means rigidly secured to said rim adjacent the peripheral surface thereof and having a passage through which the threaded portion of said binding passes, and a nut screwed on said threaded portion cooperating with the means rigidly secured to the rim to provide the desired tension in said binding.

5. A filtering element comprising a rim having a groove in the peripheral surface thereof, a disc of a filtering medium on at least one face of the rim and having the marginal portion thereof disposed in said groove, a binding disposed in said groove and on said marginal por-

tion to secure said marginal portion in said groove, said binding being wound in said groove and extending over at least the entire circumference thereof, one end of said binding being secured adjacent the periphery of said rim, said binding having a threaded portion adjacent the other end thereof, a lug rigidly secured to said

rim adjacent the peripheral surface thereof and having a slot through which the threaded portion of the binding passes, and a nut screwed on said threaded portion of said binding and co-operating with the lug to provide the desired tension in said binding.

CLAUDE FRANCOIS ALBERT CHAMOUTON.
